AUTOMATIC JACK RAFTER BEVEL SQUARE

Philander F. Witter, Kentfield, Calif.

Application June 26, 1945, Serial No. 601,683

5 Claims. (Cl. 33—90)

1

An object of my invention is to provide an automatic jack rafter bevel square which is an improvement over my Patent No. 2,340,032, issued on January 25, 1944, for an automatic jack rafter bevel square. In the patent I show the device as comprising a body member adapted to be placed against the side of a jack rafter, the body having a head designed to rest on the rafter when the instrument is used. The body also has an arm pivotally secured thereto and a quadrant with an arcuate slot and a set screw for securing the arm to the quadrant in adjusted position.

In the present form of the invention, the arm is pivotally secured to the body of the instrument and has a link connection between itself and a carriage which is slidably connected to the body. Markings or calibrations on the body indicate the position of the carriage for holding the arm at the desired angle for marking a line on the jack rafter. The line shows the angle of cut to be made.

The present device is designed to be manufactured at less cost than the one shown in my patent and the body is formed of sheet metal that is shaped in a particular manner. The angle indicating arms are pivoted directly to the body. The entire device is designed to be stamped from sheet metal and the structure is such that the device is simple and will be strong and durable for the purpose intended.

Other objects and advantages will appear in the following specification, and the novel features of the device will be particularly pointed out in the appended claims.

My invention is illustrated in the accompanying drawings forming a part of this application, in which:

Figure 1 is a perspective view of the device shown applied to a jack rafter for the purpose of marking cutting lines on the top and side of the rafter;

Figure 2 is a plan view of the device showing the parts in folded position;

Figure 3 is a side elevation of Figure 2;

Figure 4 is an end elevation of Figure 2; and

Figure 5 is a schematic view illustrating a hip rafter with two jack rafters extending therefrom.

While I have shown only the preferred forms of my invention, it should be understood that various changes or modifications may be made within the scope of the appended claims without departing from the spirit and scope of the invention.

In carrying out my invention I provide a jack rafter bevel square that has a body member A.

2

This body is preferably made of sheet metal and has inclined sides 1 and 2 that extend throughout the length of the body and cause the body to take the shape of a channel with obtusely inclined sides. The sides 1 and 2 have edges 3 and 4 that are coextensive therewith and are preferably beveled so that the edges will lie in a plane that parallels a plane coinciding with the central portion 5 of the body. The central portion is slotted at 6 and this slot extends throughout a substantial length of the body and is disposed midway between the sides 1 and 2.

An arm B is pivotally secured to the body and in actual practice the arm is formed from a strip 15 of metal that is bent to form two parallel spaced portions 7 and 8 and these portions straddle and are pivotally secured to a lug 9 by a pin 10 or other suitable supporting means. The lug 9 is carried by the body A. The two arm portions 7 and 8 are formed into a loop 11 and this loop has a width equal to that of the body and has ears or lugs 12 and 13 that project beyond the sides of the loop. The ears 12 and 13 take the place of the pin shown in my patent.

25 A link 14 is pivotally secured to the spaced parallel portions 7 and 8 of the arm B at 15 and the link is received between the parallel portions. A carriage C, see Figure 1, is slidable along the body A and a set screw 16 extends through the 30 carriage and through the slot 6. The set screw has a head 17 bearing against the underside of the central portion 5 of the body. The carriage C has an integral sleeve 18 through which the screw 16 slidably extends and a nut 19 is threaded upon the screw and is tightened for securing the carriage in adjustable position along the body A. Figure 1 shows the link 14 pivotally connected to the carriage C at 20.

Figure 2 shows the body A calibrated at 21 for 40 indicating where the carriage C is to be placed when the arm B is to extend at a predetermined angle with respect to the plane of the central portion 5. Figure 3 shows the left hand end of the carriage C beveled at 22 and the beveled edge is 45 brought into registration with the desired calibration. For example, the calibration mark "6" stands for a six-inch rise and the calibration mark "12" stands for a twelve-inch rise for every twelve-inch run.

50 I provide angle indicating arms D and E and these are pivoted to the inclined sides 1 and 2 of the body A at 23 and 24, respectively. Each arm has a projection adjacent to the pivot that extends at right angles to the length of the arm. 55 Both Figures 2 and 4 show the arm D provided

with a projection 25 and the arm E provided with a projection 26. Figure 4 illustrates the projections 25 and 26 as lying in a plane that passes through the edges 3 and 4 and that is parallel to the central portion 5. When the arms D and E are not used, they will extend along the inclined sides 1 and 2 and overlie them. The projections 25 and 26 constitute handles for initially swinging either arm into an angular position with respect to the body A.

From the foregoing description of the various parts of the device, the operation thereof may be readily understood.

In Figure 5 I indicate a hip rafter F and also show a right and left hand jack rafter G. It is necessary to make a side cut on the jack rafter at 27 and a rise cut on the same rafter at 28. Figure 1 illustrates a perspective view of the jack rafter G with the top of the rafter indicated at 29 and the side at 30. The carpenter determines what run and rise are desired and swings the arm B until the carriage registers with the desired calibration and then tightens the nut 19.

Either the arm D or the arm E is now swung into open position, this depending on whether a right or a left hand rafter is to be cut. The device is placed on the jack rafter G in the manner shown in Figure 1. This figure shows the arm E extended and resting on the top surface 29 of the jack rafter. The ear 13 of the arm B also rests on the top surface 29 and the edge 4 of the inclined body side 2 bears against the side 30 of the jack rafter.

The instrument as shown in Figure 1 is set for marking the rise line 31 and this line will extend at right angles to the rafter top 29. In actual practice the line 31 will coincide with the edge 4 of the body since the edge will act as a guide for the marking instrument, but for the purpose of clarity, the line 31 is shown moved to the right of the body A in Figure 1. The arm E will extend at the desired angle across the top 29 of the rafter and a side bevel line 32 can be drawn on the surface 29, using the arm E as a guide. In Figure 1 the line 32 will extend at about 45 degrees to the plane of the rafter side 30. As already stated, the drawing shows the instrument backed away from the lines 31 and 32.

The broken lines 33 and 34 indicate the rise angle and the side bevel angle, respectively, when the arm B has been swung into a position to cause the carriage C to register with the mark "6" of the calibrations 21. Since the arm E is pivotally secured to the body at 24, it will swing down to contact with the rafter top 29 regardless of the angle assumed by the base A on the rafter side 30. It will be seen from this that regardless of the angular position of the body A on the rafter side 30, the arm E (or the arm D) when brought into contact with the rafter top 29, will extend at the required angle across the top.

The carpenter can draw two lines on the rafter's side and top corresponding to the angles made by the body A and the arm E and then the rafter can be cut along these two lines. The cut piece X is discarded and the cut end of the rafter will now fit the hip rafter F as indicated in Figure 5. When jack rafters on the opposite side of the hip rafter are to be cut, the arm D is used in place of the arm E. After the device has been used, it may be folded into a compact position as shown in Figures 2 and 3 and the device is small enough to be readily slipped into

the pocket. When the arm D is used for marking purposes, the lug or ear 12 will rest on the top surface of the jack rafter. The arms D and E swing in planes that extend at angles of 135 degrees with respect to the plane in which the arm B swings.

The calibrations 21 take into account that the device is to be supported on the rafter D by either one of the ears 12 or 13, and that the device is also supported by either one of the arms D or E. The arm B will extend at an angle with respect to the rafter top when the device is used, but this angle has been taken into consideration in the designing of the instrument, so that the body A and either one of the arms D or E will extend at the proper angle on the rafter when the arm B has been set at the desired angle. When the arm B has been adjusted to the pitch of the roof and the device placed on the rafter, the arm D or arm E will be self-adjusting and when swung into contact with the rafter top, it will indicate the desired side cut angle at which the rafter must be cut. The arm D or E automatically assumes the proper angle for the side cut as soon as the arm is brought into contact with the top surface of the rafter.

The device does away with the necessity of using a carpenter's right angle square and figuring out the desired angles from the numbers on the square. All mathematical figuring which the square requires to be accomplished by the person using it, is automatically accomplished by the mere placing of applicant's instrument on the rafter after the required setting of the arm B has been made.

The projection 25 or 26 can be used as a support for the instrument when the arms D and E are closed and the device is used as a bevel square. For example, the arm E in Figure 1 can be swung into closed position and then the projection 26 can rest on the surface 29 to support the device. The body A will extend along the surface 30 to indicate the desired bevel and then the line 31 can be marked on the surface 30.

I claim:

1. A jack rafter bevel square comprising an elongated body, an arm pivotally secured to the body and swingable in a plane that bisects the length of the body and is perpendicular thereto, means including an adjustable brace extending from the arm to the body for securing the arm in different angular positions, an abutment carried by the outer end of the arm, and a second arm pivoted to the body and swingable in a plane in which the first arm swings, said abutment and second arm adapted to rest on a jack rafter in a position to permit the elongated body to lie against the side of the rafter.

2. In a jack rafter bevel square, an elongated body having obtusely inclined sides that make angles of 135° to a plane bisecting the length of the body and extending perpendicular thereto, the free edges of the inclined sides constituting ruling edges for guiding a pencil when marking a rafter, a pair of arms pivoted to the sides and swingable in planes paralleling the planes of the sides, and means including either one of the arms for supporting the device on a rafter in a predetermined manner so that the body will indicate the angle of the rise cut to be made on the rafter side and the supporting arm will indicate the angle of the side bevel cut to be made on the rafter top.

3. A jack rafter bevel square comprising an

elongated body, an arm pivotally mounted on the body and being swingable in a plane that parallels the body length and that is perpendicular to the body, a pair of laterally extending abutments carried by the outer end of the arm and designed to rest on a rafter top, a pair of arms pivoted to the body and either one of which when extended will act as a second support for the device, said pair of arms being swingable in planes that extend at right angles to each other and at angles of 135° to the plane of the first-named arm, a carriage slidably mounted on the body, a link connecting the carriage with the first-named arm, means for securing the carriage to the body in adjusted position for holding the first-named arm at the desired angular position with respect to the body, said body having calibrations placed in the path of the carriage for indicating various rafter pitches, whereby a placing of the device on a rafter so that one of the abutments and one of the pair of arms will be supported by the rafter top, will dispose the body against the rafter side so that the rafter can be marked along the body side and supporting arm for indicating the proper angles for the rise cut and side bevel cut on the rafter.

4. In a jack rafter bevel square, an elongated body made of sheet metal and having obtusely inclined sides that make angles of 135° to a plane bisecting the length of the body and extending perpendicularly above the body top, a pair of arms, each one being pivotally secured to a side and swingable in a plane paralleling the side, a third arm pivoted to the body and swingable in the perpendicularly extending plane, the free end of the third arm having laterally pro-

jecting abutments, said body being longitudinally slotted, a carriage slideable along the slot, a link pivotally connecting the third arm with the carriage, and means for securing the carriage to the body, said body having calibrations for indicating where to position the carriage for holding the third arm at the desired angle.

5. In a jack rafter bevel square, an elongated body made of sheet metal and having obtusely inclined sides that make angles of 135° to a plane bisecting the length of the body and extending perpendicularly above the body top, a pair of arms, each one being pivotally secured to a side and swingable in a plane paralleling the side, an arm pivoted to the body and swingable in the perpendicularly extending plane, the free end of the last-named arm having laterally projecting abutments, said body being longitudinally slotted, a carriage slideable along the slot, a link pivotally connecting the second arm with the carriage, and means for securing the carriage to the body, said body having calibrations for indicating where to position the carriage for holding the second arm at the desired angle, said pair of arms having a laterally extending projection disposed adjacent to the pivot connection made between the arm and the inclined side.
